BACKFIRE RELEASE FOR INTERNAL COMBUSTION ENGINES

Filed Oct. 31, 1931

UNITED STATES PATENT OFFICE

2,125,370

BACKFIRE RELEASE FOR INTERNAL COMBUSTION ENGINES

Malcolm P. Ferguson, Elmira, N. Y., assignor to
Eclipse Machine Company, Elmira, N. Y., a
corporation of New York

Application October 31, 1931, Serial No. 572,258

15 Claims. (Cl. 290—38)

This invention relates to a back-fire release for internal combustion engines and more particularly a device for minimizing the effect of backward rotation of an internal combustion engine 5 on the auxiliary mechanism thereof and especially on the starting mechanism therefor.

It is well known that the accidental actuation of the starting mechanism when an internal combustion engine is rotating backward causes heavy 10 stresses to be developed which may cause failure of the parts. When an automatic starting mechanism is employed for causing the engine to be cranked repeatedly until a successful start is secured, it therefore becomes important to prevent 15 the operation thereof during backward rotation of the engine.

It is an object of this invention to provide novel means to prevent actuation of a starting mechanism during reverse rotation of the internal 20 combustion engine.

Another object of the invention is to provide an automatic starting mechanism having novel means to maintain the starting mechanism inoperative while the engine is rotating backward.

25 A further object is to provide a novel device for use in connection with automatic starting mechanism for rendering such starting mechanism inoperative during reverse rotation of the engine, but automatically restoring the starting 30 mechanism to operative condition when the reverse rotation ceases.

Further objects and advantages will be apparent to those skilled in this art from the following description taken in connection with the accompanying drawing in which:

Fig. 1 is a semi-diagrammatic view of a preferred embodiment of the invention shown in connection with an automatic starting mechanism of known type; and

40 Fig. 2 is an enlarged mid-sectional view of the back-fire releasing device.

Referring to the drawing, an electrical starting system for an internal combustion engine (not shown) is illustrated comprising a battery 1 45 grounded at 2 and connected to a starting motor SM through a lead 3 and an automatic controlling device indicated generally at 4 and comprising a starting switch 5 adapted to be closed by energization of a solenoid 6. Solenoid 6 is embodied

50 in a control circuit including the ignition switch 7 of the engine, lead 8, lead 9, contacts 11 and ground connection 12. Contacts 11 are arranged to be opened by the action of a lever 13 which is moved by a solenoid plunger 14 to bend back 55 the spring strip 15 carrying one of the contacts

11 when the engine starts. The plunger 14 is maintained in its lower position by means of a coil 16 energized from the generator G while the engine is in normal operation.

The device so far described and the operation thereof are known in the art, but it has been found that the generator coil 16 as usually constructed is not energized by the generator G sufficiently to retain the plunger 14 in its retracted position when the engine is rotating backward 10 such as occasionally occurs for instance in the case of back-fire.

The present invention provides means to prevent the reactivation of the starting mechanism during back-fire conditions in spite of the de- 15 energization of the generator coil 16, and the present embodiment employs for this purpose a device for breaking the control circuit of the solenoid 6 during backward rotation of the engine. As best shown in Fig. 2, this device com-

20 prises a casing 17 connected to the intake system of the engine as by means of an extension 18 threaded into the intake manifold of the engine, a portion of which is indicated at 19. A metallic diaphragm 21 is rigidly mounted in the casing 25 17 in a manner to form a closed chamber 22 in such casing, which chamber is in communication with the gases in the intake manifold through a passage 23 in the threaded extension 18. The diaphragm 21 is insulated from the casing as indicated at 24 and is connected as by means of a lead 25 to an insulated binding post 26 in the side of the casing. A contact 27 is carried by the diaphragm in position to normally engage a fixed contact 28 mounted on a bracket 29 connected 30 to a second insulated binding post 31 in the side of the casing. The space 32 above the diaphragm is preferably vented to the atmosphere as indicated at 33, and a spring 34 is preferably provided for insuring the normal engagement of contacts 35 27 and 28.

The back-fire releasing device is placed in the control circuit of solenoid 6, and, as shown in Fig. 1, is preferably inserted in the lead 8 of the control circuit, the ends thereof being attached to 45 the binding posts 26 and 31 whereby the contacts 27 and 28 are placed in series in the controlling circuit, and opening of said contacts renders solenoid 6 inoperative.

In operation, and starting with the parts in the 50 positions illustrated, closure of the ignition switch 7 causes energization of the solenoid 6 to close the starting switch 5 and cause the engine, not illustrated, to be cranked. If the engine starts properly, the control plunger 14 is moved to open 55

contacts 11 and is held in its retracted position by the generator coil 16 as long as the engine is running. However, if the engine should give one or two explosions sufficient to disconnect the starting gearing and thereafter should back-fire, the generator coil 16 is deenergized and the contacts 11 allowed to close. The immediate operation of the starting mechanism is prevented, however, since the backward rotation of the engine 10 operates as a pump to force gas back into the intake system, thus creating a pressure therein which is increased by the back-firing explosions. This pressure in the intake system is transmitted through the passage 23 to the diaphragm 21 causing the contact 27 to be moved away from contact 28, thus breaking the control circuit for the solenoid 6 and preventing closing of the starting switch as long as the pressure in the intake manifold persists. When the backward rotation ceases, the pressure in the intake system 15 is dissipated and the diaphragm 21, assisted if necessary by the spring 34, returns the contact 27 into engagement with fixed contact 28, thus completing the control circuit and causing the cranking operation to be repeated.

In order to provide sufficient time delay to ensure the opening of contacts 27, 28 by the intake pressure before effective closure of contacts 11, the spring strip 15 is provided at its 20 free end with a weight 18 which, when released by the lever 13, vibrates the spring strip for a suitable time before coming to rest and permitting effective closure of contacts 11.

It will thus be seen that there is here provided a device which automatically prevents the actuation of the starting mechanism while the engine is rotating rearwardly, but which restores the parts to operative condition when the rearward rotation ceases. It will be understood that the invention is not restricted to the details of 40 the embodiment illustrated, since other embodiments utilizing the principles of the invention will readily suggest themselves to those skilled in the art, and since various changes may be made in the arrangements and methods of cooperation 45 of the parts without departing from the spirit of the invention as defined in the claims appended hereto.

What is claimed is:—

1. In combination with an internal combustion engine having a fuel intake system and starting mechanism therefor, means actuated by positive pressure in the intake system of the engine greater than atmospheric pressure for preventing actuation of the starting mechanism.
2. In combination an internal combustion engine having an intake system functioning at sub-atmospheric pressure during normal operation of the engine, starting mechanism therefor including a starting switch, manually controllable means for actuating said starting switch, and means responsive to positive pressure in said intake system for preventing the actuation of said starting switch.
3. In combination with an internal combustion engine having a fuel intake system, a starting mechanism therefor including a starting switch, means including a control circuit for actuating said starting switch, and means responsive to positive pressure in the intake system of the engine above atmospheric pressure for preventing actuation of the control circuit to close the starting switch.
4. In combination with an internal combustion engine having a fuel intake system, an

automatic starting mechanism therefor including manually controllable means for cranking said engine whenever forward rotation thereof ceases, and means actuated by positive pressure in the intake system of the engine above atmospheric pressure for preventing such cranking, said latter means being arranged to cause cranking to take place automatically as soon as the positive pressure in the intake system of the engine is dissipated.

5. An automatic controller for internal combustion engine starters comprising with an internal combustion engine, a starting motor circuit, an electro-magnetic switch in said circuit for controlling energizing of the motor, a relay 15 controlling the energizing of said electro-magnetic switch and including contacts, and means actuated by pressure above atmosphere in the intake manifold for maintaining said contacts separated.

6. An automatic controller for internal combustion engine starters comprising with an internal combustion engine, a starting motor circuit, an electro-magnetic switch in said circuit for controlling energizing of the motor, a relay 25 controlling the energizing of said electro-magnetic switch and including contacts, and means actuated by pressure above atmosphere in the intake manifold for maintaining said contacts separated, said means including a flexible dia- 30 phragm.

7. An automatic controller for internal combustion engine starters comprising with an internal combustion engine, a starting motor circuit, an electro-magnetic switch in said circuit for 35 controlling energizing of the motor, a relay controlling the energizing of said electro-magnetic switch and including contacts, and means actuated by pressure above atmosphere in the intake manifold for maintaining said contacts separated, said means including a movable member subjected to such pressure.

8. In an automatic controller for internal combustion engine starters, an ignition circuit, a starting motor circuit, and means comprising 45 a pressure-operated device for maintaining said starting motor circuit open after ignition occurs when pressure above atmosphere exists in the engine manifold.

9. In an automatic controller for internal combustion engine starters, an ignition circuit, a starting motor circuit, and means for maintaining said starting motor circuit open after ignition occurs when pressure above atmosphere exists in the engine manifold, comprising a pair 55 of contacts and a pressure-operated device for opening said contacts.

10. In combination with an engine rotatable in opposite directions but operable in only one direction, and automatic starter operating 60 mechanism, said mechanism being effective upon the cessation of operation of said engine, of fluid pressure means associated with said mechanism and said engine to render the mechanism inoperative while said engine is rotating in a reverse direction.

11. In combination with an engine having a manifold and an automatic starter operating mechanism, of fluid pressure controlling means associated with said mechanism, said means being associated with the manifold to render said mechanism inoperative while reverse engine rotation is occurring, and operative thereafter.

12. In combination, an engine, a starter, and an automatic starter actuating system opera- 75

5 tive, upon stalling of the engine, to actuate the
6 starter, means associated with said system tend-
7 ing to render it inoperative during back-firing of
8 the engine, and automatic means associated with
9 said system tending to render it operative upon
10 final stopping of the engine.

11 13. In an engine, the combination with an en-
12 gine starting system including a starter device
13 having automatic energizing control means as-
14 sociated therewith effective upon stopping of the
15 engine, of fluid pressure means associated with
16 said system automatically to render said control
17 means inoperative when the engine back-fires
18 and automatically to render said control means
19 operative when the engine stops after back-fir-
20 ing.

21 14. In an automatic controller for internal
22 combustion engine starters, a starting motor cir-
23 cuit, and means comprising a pressure-operated
24 device for maintaining said starting motor cir-
25 cuit open when pressure above atmospheric ex-
26 5 ists in the engine intake manifold.

27 15. In an automatic control for internal com-
28 bustion engine starters, a starting motor circuit,
29 and means for maintaining said starting motor
30 circuit open when pressure above atmospheric 10
31 exists in the engine intake manifold comprising
32 a pair of contacts, and a pressure-operated de-
33 vice for opening said contacts.
